WINDMILL REGULATOR

Filed Jan. 26, 1922

2 Sheets-Sheet 2

UNITED STATES PATENT OFFICE.

JOHN M. LOWE, OF BUTLER, INDIANA.

WINDMILL REGULATOR.

Application filed January 26, 1922. Serial No. 531,951.

To all whom it may concern:

Be it known that I, JOHN M. LOWE, a citizen of the United States, residing at Butler, in the county of Dekab and State 5 of Indiana, have invented a new and useful Windmill Regulator, of which the following is a specification.

This invention aims to provide a novel and efficient means whereby the operation 10 of a wind mill may be controlled automatically.

It is within the province of the disclosure to improve generally and to enhance the utility of devices of that type to which the 15 invention appertains.

I do not bind myself to the specific details of construction depicted and described, for, although the drawings show a preferred embodiment of the invention, a mechanic, 20 working within the scope of what is claimed, and exercising such skill as might be expected of him, may make changes, without departing from the spirit of the invention, or jeopardizing the utility of the device.

25 In the accompanying drawings:—Figure 1 shows, in elevation, a device constructed in accordance with the invention, the tank appearing in section; Figure 2 is an elevation showing a portion of a wind mill post, 30 the device forming the subject matter of this invention being mounted thereon, parts being omitted, and parts appearing in section; Figure 3 is a vertical section on the line 3—3 of Figure 2; Figure 4 is a cross section on the line 4—4 of Figure 3; Figure 35 5 is a cross section on the line 5—5 of Figure 3; Figure 6 is a sectional detail illustrating a modification.

The numeral 1 designates, generally, the 40 tower of a wind mill, embodying an inwardly inclined post 2, a cross brace 3, and other common parts, the pump rod being marked by the numeral 4 and being operated from the wind wheel (not shown), in the usual 45 manner, through the instrumentality of a gearing (likewise not shown), whereby the wind wheel may be stopped and started at will.

The post 2 carries a support, denoted generally by the numeral 5, the support being a composite structure, and including side plates 6 and 7, having flanges 8 adapted to engage the post 2, as shown in Figure 4, the side plates being connected, and being held 55 upon the post 2, by an upper securing element or bolt 9 and a lower securing element

10, which connect the plates adjacent to the post. On its inner side, the plate 6 is supplied with a pocket 11, having the function of a pawl-stop, as hereinafter explained, 60 the pocket and the plate 6 carrying an upper socket 12 and a lower socket 14. One end of a pivot pin 15 is secured in the socket 14, the corresponding end of a fulcrum pin 16 being secured in the socket 12, the pins 15 65 and 16 being slidable in the plate 7, the construction being such that the plate 7 may be adjusted toward and away from the plate 6, so as to accommodate tower posts 2 of different widths. The plate 7 may be supplied with a boss 17, wherein the fulcrum pin 16 is received, a set screw 18 being threaded into the boss and engaging the pin 16, the pin, therefore, cooperating with the securing elements 9 and 10, to aid in holding 70 the support 5 on the post 2.

The numeral 19 marks a lever which is mounted to swing vertically on the fulcrum pin 16, in engagement with the socket 12, a cotter pin 20 or the like being carried by the 80 pin 16, to hold the lever 19 in place, as shown in Figures 2 and 4. At its inner end, the lever 19 has a fork 21, an actuating pawl 22 being disposed within the fork, and being pivoted thereon at 23. The outer end 85 of the actuating pawl is weighted as at 24, so as to throw the opposite end of the pawl inwardly, the last specified end of the pawl being provided with a lateral finger 25, received within the pocket 11 of the side plate 6, the inner wall of the pocket cooperating 90 with the finger to serve as a stop for the pawl. A back stop pawl 26 is mounted to swing on the pivot pin 15 and is held in engagement with the socket 14 by means of a cotter pin 27 carried by the pivot pin 15. It will be observed that the lever 19, the actuating pawl 22 and the back stop pawl 26 cannot move horizontally with respect to the side plate 6, the support 5 being expanded or 95 contracted, to fit different sizes of posts, by shifting the side plate 7 with respect to the side plate 6 and with respect to the pawl 26, the pawl 22 and the lever 19. The back stop pawl 26 is weighted at its upper end, as at 100 28, so as to throw the lower end of the pawl inwardly, the inward movement of the pawl being limited, however, by a lateral finger 29 on the pawl, this finger being adapted to cooperate with a lug 30 which projects inwardly from the side plate 6.

The lever 19 includes an extension 31,

whereon a rider 32 is mounted for adjustment, longitudinally of the lever, the rider being held in adjusted positions by a set screw 33, which, being threaded into the 5 rider, bears on the extension 31 of the lever. The lower ends of links 35 are pivoted at 34 to the rider 32, the upper ends of the links being united by a clamping bolt 36. The numeral 37 marks a connecting member, which may be a wire, the lower end of the connecting member having a loop 200 engaged about the bolt 36 and clamped between the upper ends of the links 35, the construction being such that the length of 10 the connection 37 may be adjusted. The upper end of the connecting member 37 is attached to a bracket 38, mounted on the pump rod 4, it being noted, incidentally, at this point, that the pump rod serves to impart vertical swinging movement to the 15 lever 31-19.

A radius arm 39 is located between the side plates 6 and 7 of the support 5, and is mounted to swing on the lower securing 20 element 10 which unites the plates. An L-shaped latch 40 is provided, one end of the latch being pivoted at 41 to the upper end of the radius arm, the other end of the latch extending outwardly across the upper edge 25 of the side plate 6, and being adapted to cooperate with shoulders 201 and 42 formed therein. The numeral 43 marks a trip lever, placed externally of the plate 6 and fulcrumed intermediate its ends thereon as at 30 44, swinging movement of the lever being limited by stops 45 and 145 on the plate. A headed detent 72 is slideable in the plate 6, transversely thereof, and may be advanced into the path of the trip lever 43, 35 for a purpose which will be explained hereinafter. A weight 46 is adjustable along the trip lever 43 and is held thereon by a set screw 47, threaded into the weight and adapted to engage the lever. One end of 40 a flexible element 48, such as a light chain, is connected to the weight 46, the flexible element being rove through a block 49 mounted pivotally on the cross brace 3 of the tower 1. From the block 49, the flexible element 48 extends downwardly across 45 a guide sheave 50, journaled on a standard 51 carried by a tank 52. A float 53 is located in the tank 52, the flexible element 48 being attached to the float. The wind 55 mill operates the rod 4; the pump of which the rod 4 is a part delivers water to the tank 52 through a pipe 54; and, as shown in Figure 1, the float 53 is supported on the liquid in the tank.

A guide 55 is pivoted at 56 to the radius arm 39, intermediate the ends thereof, and in the guide, a rack bar 57 is mounted for reciprocation, an offset extension 58 being secured at 59 to the upper end of the rack bar. The teeth of the rack bar are marked

by the numeral 60, and, above the teeth, there is a smooth surface 61, located on the rack bar and on the extension 58 thereof.

A slide 62 reciprocates on the post 2. The slide 62 comprises a body or block 63, 70 having an outer groove 64 in which the upper end of the extension 58 of the rack bar 57 is received, the inner surface of the block or body 63 being provided with a groove 65, disposed at right angles to the groove 64 and receiving a pair of overlapped members 66 and 67 having flanges 68 engaged loosely around the post 2. A securing element, such as a screw 69, passes through the upper end of the extension 58 of the rack 75 bar 57 and through the block 63, the securing element being mounted in the member 66, and the member 67 having a slot 70 through which the securing element 69 passes, the members 66 and 67 being bound firmly upon the block 63 by the securing element. It is to be noted that the member 66 is fixed relative to the block 63, whereas the member 67 may be adjusted with respect thereto, to accommodate posts 2 of 80 different widths. The lever 19-31 and the pawls 22 and 26, it will be recalled, are fixed against lateral movement with respect to the plate 6, the adjustment in the width of the support 5 being brought about by 85 shifting the plate 7 inwardly or outwardly. Since the member 66 is fixed with respect to the block 63, the member 67 being adjustable, the rack bar 57 is always held in alignment with the pawls 22 and 26, so as to coact therewith, even though the support 5 and the slide 62 may have been increased or diminished in width, to fit posts of 90 different sizes. Since the slide 62 is mounted somewhat loosely on the post 2, the slide 95 may not only move longitudinally of the post, but, as well, may tilt thereon, and because the slide can tilt on the post, the rack bar 57 is permitted to have a slight swinging movement in the direction of the arrows A and B in Figure 3, to the end that the rack bar may be brought into and out of engagement with the pawls 22 and 26. To the upper end of the extension 58 of the 100 rack bar 57, a connecting element 71 is secured, this connecting element extending upwardly, and being connected operatively, 105 in the usual way, with the gearing of the wind mill, (not shown).

Suppose that the tank 52 is filled to the 110 desired level. Then, the trip lever 43, responding to the weight 46 rests on the stop 145 and is out of engagement with the latch 40, the latch being engaged with the shoulder 42, the radius arm being swung into the 115 position shown in Figure 3, the rack bar 57 being swung away from the post 2, the teeth 60 of the rack bar being engaged with the back stop pawl 26 and with the actuating pawl 22, and the detent 72 having been 120

5 moved inwardly, from the position of Figure 4, so that the detent does not overhang the trip lever 43. The rack bar 57 and the connecting element 71 are held against upward movement, and the wind mill will be held out of gear.

10 Suppose, now, that the level of the liquid in the tank 52 falls. Then the float 53 will move downwardly, the flexible element 48 running over the block 49 and raising the weighted end of the trip lever 43 until the opposite end of the trip lever engages the stop 45, and until the trip lever engages the latch 40 and swings the latch at 41 on the 15 radius arm 39, until the latch is disengaged from the shoulder 42. Thereupon, the rack bar 57 swings in the direction of the arrow B, responsive to the pull on the connecting element 71, the latch 40 engaging 20 behind the shoulder 201, and the guide 62 acting as a fulcrum, it being recalled that the guide is loosely engaged with the post 2, as shown in Figure 5. The radius arm 39 swings on its fulcrum 10, in the direction 25 of the arrow B. When the rack bar 57 is swung in the direction of the arrow B, the teeth 60 of the rack bar are disengaged from the pawls 26 and 22, and the rack bar and the connection 71 moving upwardly, responsive to the pull on the connection, from the gearing of the wind mill. The wind mill, thus, will be thrown into gear and will start to operate. The swinging movement of the actuating pawl 22, under its weighted end 24, is limited by contact between the finger 25 on the pawl and the rear wall of the pocket 11 on the plate 6. The swinging movement of the back stop pawl 26, due to its weighted end 28, 30 is limited by contact between the finger 29 on the pawl and the lug 30 on the plate 6.

35 When the wind mill is thrown into gear, as above explained, the pump rod 4 is reciprocated, water is discharged through the pipe 54 into the tank 52, and the float 53 rises. The weighted end of the trip lever 43 moves downwardly, the member 71 is not under tension when the mill is in gear the 40 latch 40 being disengaged by the trip lever 43 from the shoulder 201. The post 2 is inclined inwardly, and, consequently, the rack bar 57 swings by gravity in the direction of the arrow A, with the guide 62 as a fulcrum, until the teeth 60 of the rack bar 55 cooperate with the pawls 22 and 26. When the rack bar 57 swings in the direction of the arrow A, as aforesaid, the latch 40 is advanced, through the instrumentality of the member 55 and the radius arm 39, until the latch interlocks with the shoulder 42.

45 The pump rod 4, reciprocating, transmits motion to the lever 31-39 by way of the connecting member 37, the links 35 and the 50 rider 32, the actuating pawl 22 forcing the

50 rack bar 57 downwardly, and the back stop pawl retaining the rack bar whilst the actuating pawl 22 is securing a new hold on the rack bar. When the rack bar 57 and the connecting element 71 are carried downwardly, the mill is thrown out of gear, and the delivery of water through the pipe 54 to the tank 52 stops. Ordinarily, the actuating pawl 22 is on the uppermost tooth 60 of the rack bar 57 by the time that the mill 55 is out of gear, but if, for any reason, a further downward movement of the rack bar should take place, to a slight extent, the actuating pawl 22 will ride upon the smooth surface 61 of the rack bar, and the rack 60 bar will be forced downwardly no further.

65 One of the main advantages of the device arises out of the fact that the rack bar 57 is swung into and out of engagement with the pawls 22 and 26, instead of swinging 70 the pawls into and out of engagement with the rack bar. Owing to the fact that the rack bar 57 is the moving element, the tripping operation takes place with the expenditure of less energy than would be called for 75 otherwise.

80 The construction of the device is such that the float 53 need be heavy enough only to keep a tension on the flexible element 48 and to overcome the weight 46 on the lever 43, it 85 being observed that, by loosening the screw 47, the weight 46 may be shifted on the lever 43 until a fine balance between the weight 90 and the float 53 is secured.

95 The stroke of the lever 31-19 may be 100 adjusted by shifting the rider 32 on the part 31 of the lever, and, through the instrumentality of the set screw 33, the rider may be held in any desired position, and a fine 105 adjustment in the position of the rider may be attained.

110 As shown in Figure 1, the device may be located relatively near to the bottom of the tower 1, and is accessible for cleaning, repair or adjustment, at the hand of a person 115 standing on the ground.

120 The device may be operated by hand, and when a hand operation is desired, the trip lever 43 is raised, and the detent 72 is advanced beneath it, whereupon the mill will 125 be thrown into gear and will remain in that condition until the detent is retracted. If the detent 72 is advanced over the upper edge of the trip lever 43, as shown in Figure 4, the mill will be placed out of gear 130 and will so remain until the detent is thrust inwardly.

135 If desired, the rider 22 may be detached from the extension 31 of the lever 19, and, then, the device may be operated by hand.

140 One advantage of the device is that the pawls 22 and 26 either are fully engaged with the teeth 60 of the rack bar 57 or are fully out of engagement therewith, the pawls never operating with a partial or 145

insecure hold on the teeth 60 of the rack bar, and there being, consequently, no breaking of the working ends of the pawl, or a stripping of the teeth 60 of the rack bar.

5 In the foregoing discussion, it has been presupposed that the trip lever 43 is operated by the float 53 in the tank 52. The device, however, will operate successfully in connection with a pneumatic system. Thus, 10 in Figure 6, the numeral 73 marks a pressure pipe, wherewith a casing 74 communicates, the casing containing a yieldable diaphragm 75, responsive to pressure in the pipe 73. A plunger 76 slides in the casing 15 74 and includes a foot 77 resting on the diaphragm 75. A lever 78 is supported intermediate its ends on the plunger 76, and is fulcrumed at 79 on the casing, the lever carrying a weight 80, held in adjusted positions by a set screw 81, a flexible element 82 being connected to the lever 78, and corresponding in function to the flexible element 48 of Figure 1.

Having thus described the invention, 25 what is claimed is:

1. A wind mill regulator comprising a support; a lever fulcrumed thereon; a pawl carried and operated by the lever; a rack bar cooperating with the pawl; and means 30 for mounting the rack bar for longitudinal sliding movement, and for transverse movement into and out of engagement with the pawl.

2. A wind mill regulator comprising a support; a lever fulcrumed thereon; a pawl carried and operated by the lever; a rack bar cooperating with the pawl; means for mounting the rack bar for longitudinal sliding movement, and for swinging movement 40 into engagement with the pawl; and means for swinging the rack bar out of engagement with the pawl.

3. A wind mill regulator comprising a support; a lever fulcrumed thereon; a pawl operated by the lever; a radius arm mounted to swing on the support; a rack bar cooperating with the pawl; means for mounting the rack bar on the radius arm for longitudinal sliding movement and for swinging movement with respect thereto; a latch carried by the radius arm and adapted to interlock with the support; and trip means for the lever, the trip means being carried by the support.

4. A wind mill regulator comprising a support; a lever fulcrumed thereon; a pawl operated by the lever; a radius arm mounted to swing on the support; a rack bar coacting with the pawl; means for mounting the rack bar on the radius arm for longitudinal movement and for transverse swinging movement; a latch carried by the radius arm and adapted to interlock with the support; and a second lever fulcrumed on the

support and coacting with the latch to constitute a trip means therefor.

5. A wind mill regulator comprising a support; a lever fulcrumed thereon; a pawl operated by the lever; a rack bar cooperating with the pawl; means for mounting the rack bar for longitudinal movement and for transverse movement into and out of engagement with the pawl; a rider adjustable along the lever; means for holding the rider in adjusted positions on the lever; 70 links pivoted to the rider; a clamping element connecting the links; and a pump rod connection engaged with the clamping element and bound thereby between the links.

6. In a device of the class described, a 80 post; a support on the post; a lever fulcrumed on the support; a pawl operated by the lever; a rack bar cooperating with the pawl; a slide mounted for reciprocation on the post, and tiltable thereon to permit 85 the rack bar to move into and out of engagement with the pawl; and means for moving the rack bar out of engagement with the pawl.

7. In a device of the class described, a 90 post; a support on the post; a lever fulcrumed on the support; a pawl operated by the lever; a radius arm mounted to swing on the support; a guide pivotally mounted on the radius arm; a rack bar slidable in the 95 guide and adapted to cooperate with the pawl; a latch connected with the radius arm and cooperating with the support; a trip means on the support and cooperating 100 with the latch; a slide mounted for reciprocation on the post, and tiltable thereon; and means for securing the rack bar to the slide.

8. In a device of the class described, a support comprising a first side plate; a lever fulcrumed on the first side plate and 105 held thereon against movement toward and away from the first side plate; a pawl operated by the lever; a second side plate adjustable toward and away from the first side plate; clamping means for connecting 110 the side plates; a slide comprising a first member; a second member adjustable toward and away from the first member of the slide; means for connecting said members adjustably; a rack bar cooperating with 115 the pawl and secured to the first member of the slide; means for carrying the support fixedly, and for carrying the slide for adjustment and for tilting movement; and means for moving the rack bar out of engagement with the pawl.

In testimony that I claim the foregoing as my own, I have hereto affixed my signature in the presence of two witnesses.

JOHN M. LOWE.
